UNITED STATES PATENT OFFICE.

FRANK MICHALSKY, OF FOLEY, MINNESOTA.

MILKING-STOOL.

986,401.

Specification of Letters Patent.

Patented Mar. 7, 1911.

Application filed September 29, 1910. Serial No. 584,498.

To all whom it may concern:

Be it known that I, FRANK MICHALSKY, a citizen of the United States, residing at Foley, in the county of Benton and State of Minnesota, have invented certain new and useful Improvements in Milking-Stools; and I do declare the following to be a full, clear, and exact description of the invention, such as will enable others skilled in the art to 10 which it appertains to make and use the same.

This invention relates to an improved milking stool.

The object of the invention is to provide a 15 light strong, simply constructed cheaply manufactured stool of this character designed to support both the milker and the milk bucket and it may be readily moved from place to place.

20 With the foregoing and other objects in view, the invention consists of certain novel features of construction, combination and arrangement of parts, as will be more fully described and particularly pointed out in the 25 appended claims.

In the accompanying drawings, Figure 1 represents a perspective view of this improved stool; Fig. 2 is a longitudinal vertical section thereof.

30 In the embodiment illustrated a step-like stool 1 is shown the frame of which is preferably constructed of metal rods and the seats of heavy mesh wire or other suitable light material. The frame comprises an 35 upright inverted U-shaped rear member 2 having loops 3 formed on the ends thereof which are extended laterally to form feet. A similarly shaped horizontally disposed member 4 has the free ends thereof engaged 40 with the arms of the member 2 preferably midway the length of said arms, the looped portion thereof having a heavy mesh wire bucket support 4 secured thereto. A transversely arranged brace rod 5 connects the 45 arms of the member 2 to hold them against lateral movement.

Legs 6 and 7 are secured to the opposite sides of the member 4 and are preferably constructed of wire rods each bent intermediate of its ends to form a loop as 8 which is extended laterally to form a foot. This rod is twisted together adjacent said foot and the ends diverge and are secured by any suitable means to the side bars of the 55 member 4.

An operator supporting seat is arranged

above the member 4 and preferably comprises two rods 9 and 10 secured at one end to the arms of the member 2 adjacent its curved cross bar. These rods 9 and 10 are bent downwardly to form brace members 11 and 12 for the front of the operator's seat and are secured to the arms of the member 4 adjacent the forwardly disposed members of the legs 6 and 7. A cross bar 13 connects the two horizontally disposed rods 9 and 10 near the bends therein and a bar 14 is connected at its opposite ends to the arms of member 4 in close proximity to the ends 9 and 10. A heavy mesh wire seat 15 is connected at the edges thereof to the rods 9 and 10 and the bars 13 and 14. Diagonally arranged brace rods 16 and 17 are connected at one end to the rods 9 and 10 and at their other ends to the sides of the member 4 70 crossing each other between the upright braces 11 and 12. Two similar brace rods 18 and 19 are connected at one end to the sides of member 4 and at their other ends to the feet 8. A cross rod 20 preferably connects the sides of member 4 in advance of and adjacent to the point of connection of the rods 11 and 12 and a brace 21 connects rod 20 with rod 14.

This cheaply constructed milking stool is 85 light to handle, strong and is also weather proof and the cross bar of the member 2 which projects above the seat forms a convenient handle for carrying the device from place to place.

90 From the foregoing description taken in connection with the accompanying drawings, the construction and operation of the invention will be readily understood without requiring a more extended explanation.

95 Various changes in the form, proportion and the minor details of construction may be resorted to without departing from the principle or sacrificing any of the advantages of the invention, as defined in the appended claims.

I claim as my invention:

1. A milking stool comprising an inverted U-shaped upright member, horizontally disposed vertically spaced seat members secured at one end to said upright member, one of said horizontal members extending in advance of the other member, means connected with the lower member for supporting the front end of the upper member, and supports connected with the front end of the lower member.

- 2
2. A milking stool comprising an inverted U-shaped upright member composed of a metal rod having its end bent to form feet, a substantially U-shaped horizontally disposed member having the front ends of the legs thereof connected to the legs of said upright member at a point spaced from said feet, means for supporting the free end of said horizontally disposed member, a horizontally disposed seat member connected with said upright member at a point above said first mentioned horizontal member and having vertical supports at its front end connected with the legs of said horizontally disposed U-shaped member, and a seat arranged 15 on the front end of said horizontally disposed U-shaped member.
- In testimony whereof I have hereunto set my hand in presence of two subscribing witnesses.
- FRANK ^{his} X MICHALSKY.
